(57) **CLAIM**

I claim, the ornamental design for a firearm, as shown and described.

DESCRIPTION

FIG. 1 is a left side view of a firearm showing my new design;

FIG. 2 is a top perspective view thereof;

FIG. 3 is a partial side view taken from FIG. 1;

FIG. 4 is a partial side view taken from FIG. 1, with magazine shown in FIG. 6;

FIG. 5 is a partial side view taken from FIG. 1;

FIG. 6 is a partial side view taken from FIG. 1, showing the magazine portion;

FIG. 7 is a top view thereof;

FIG. 8 is a rear view thereof;

FIG. 9 is a right side view thereof;

FIG. 10 is a bottom view thereof; and,

FIG. 11 is a front view thereof.

The evenly broken lines in the drawings depict unclaimed portions of the firearm; the dash-dot-dot line discloses the boundary of the views only. The broken lines form no part of the claimed design.
